UNITED STATES PATENT OFFICE.

GEORGE A. LONG, OF HARTFORD, CONNECTICUT, ASSIGNOR TO THE GRAY TELEPHONE PAY STATION COMPANY, OF HARTFORD, CONNECTICUT, A CORPORATION OF CONNECTICUT.

COIN-CHUTE.

1,087,307.

Specification of Letters Patent.

Patented Feb. 17, 1914.

Application filed June 21, 1913. Serial No. 774,987.

To all whom it may concern:

Be it known that I, GEORGE A. LONG, a citizen of the United States, residing at Hartford, in the county of Hartford and 5 State of Connecticut, have invented certain new and useful Improvements in Coin-Chutes, of which the following is a specification.

This invention relates to coin chutes.

10 A coin chute involving my invention can be used in various connections, although it is of particular utility when incorporated in a telephone pay station.

One of the primary purposes of the invention is the provision of simple and effective means by which the choking or clogging of a chute by coins or tokens of irregular contour or unusual shape is prevented.

15 In the drawings accompanying and forming part of the present specification I have shown in detail one of the several convenient forms of embodiment of the invention which to enable those skilled in the art to practise the same will be set forth fully in the following description. I do not limit myself to this disclosure; I may depart therefrom in several respects within the scope of the invention defined by the claims following 20 said description.

25 Referring to said drawings: Figure 1 is a front elevation of a chute involving my invention. Fig. 2 is a view of said chute as seen from the right in Fig. 1. Fig. 3 is a view of the upper portion of said chute as 30 seen from the front, the major part of the chute being in vertical section. Fig. 4 is a front elevation of an intermediate portion of the chute, showing a token therein. Figs. 5 and 6 are cross sections on the lines 5—5 and 35 6—6 respectively of Fig. 1, the arrows on the section lines indicating the direction of view. Fig. 7 is a transverse section on the line 7—7 of Fig. 3 looking in the direction of the arrow.

40 Like characters refer to like parts throughout the several figures.

45 As I have already observed a coin chute involving my invention, can be employed advantageously in connection with various 50 kinds of coin controlled or vending machines, although it is of especial merit when embodied in a telephone pay station. In Letters Patent No. 912,389 granted to me February 16, 1909 is shown a compound 55 chute such as I employ in pay stations now

on the market. This compound chute involves three chutes one intended for nickels, another for dimes, and the third for quarters. The chute shown in the drawings may be that provided for the passage of half 60 dimes. As a matter of fact the present machine is adapted especially for use in Canada where the half dime or five-cent piece is a coin very thin and of small diameter. As will be evident the chute can be of such size 65 to receive any kind of coin or token. In Canada there has been current a small token or medal such as illustrated in Figs. 3 and 4 of the drawings, which in diameter and thickness, is about the size of a Canadian 70 half dime or five-cent piece, and it has been a common thing in the Dominion to have persons insert such a medal or token in the five-cent slot of a pay station. This token or medal, in descending the five-cent chute 75 has been wedged therein. With such a token choking the chute, it is impossible to pass proper coins therethrough to operate a signal or to effect some other end, in which event the machine becomes practically useless and has to be taken away and apart to remedy the difficulty.

With the foregoing general observations I will now describe more in detail what is illustrated in the drawings, it being clear 80 that I do not restrict myself to such disclosure as the same is merely one way of securing the objects in view.

I have denoted the chute in a general way by 2, and it comprises a lower portion 3 and 85 an upper inclined portion 4. The chute is made up of a channeled body member 5 and a facing or closing member as 6, the latter having parallel beads 7 as shown in my Patent 1,061,093 of May 6, 1913 to which reference may be had. The chute 2 has a slot 9 formed as shown in the body section thereof, said slot serving as a trap and being shown in both of the aforementioned patents and many others granted to me. Through 90 said trap or slot 9 are projected coins of improper size after the common practice.

I have shown in dotted and full lines in Fig. 3 and in full lines in Fig. 4 a token 10 with which considerable trouble has been 95 had in Canada. This device is about the same diameter as a Canadian five-cent piece, and it has a peripheral perforated projection so that it can be worn as a pendant. Such a token, owing to its shape becomes fre- 100

quently blocked in the present chutes by reason of the fact that it cannot roll therein. I provide for the rolling of such a token, or in fact one of any other character, 5 wherein one diameter is greater than the other, the increase of diameter in the token 10 in one direction with respect to the other being due to the peripheral projection to which I have alluded. The chute 2, prefer- 10 ably in the upper inclined part thereof has a relief portion which can be produced in various ways as by making said chute at such place wider than the remainder of said chute, for instance by slotting the latter as 15 at 11 to provide for the rolling of said token 10 or one of a practically similar nature along the chute, said slot 11 being formed in the present case by cutting out one of the upper side walls, (the left one in Figs. 1, 3 20 and 4), of the channel body member 5, said slot permitting the token to roll until such point as it passes from the upper inclined portion 4 of the chute into the lower vertical part 3 thereof in which case if the peripheral projection of the token be up and if the token be not trapped out of the slot 9, said token can descend through the vertical part 3. As shown, the forward or lower end of 30 the slot 11 is closed to prevent coins from jumping out of said slot. Of course in this event the token would strike the edge of the bell disposed at the discharge end of the chute 3, but it is preferable that the signal be sounded than the token choke or clog the chute. There may be times when the token 35 10 will pass entirely out the trap or slot 9. It is possible also that the token may be projected partly out of the trap as shown in Fig. 6 and will roll down until it strikes the lower wall of said trap, in which event it 40 would stop at such point and block the chute. I provide means now to be described to guard against this contingency.

The trap 9 is of obtuse angular form, ex- 45 tending partially along the chute portion 4 and partially along the chute portion 3. At the lower end of the slot or trap 9 there are two outwardly extending notches 12 shown as transversely aligned, the width of each of 50 which is greater than the diameter of the

peripheral projection to which I have referred. It will be assumed that a token such as that illustrated has been partially trapped through the slot 9 as shown in Fig. 6. It will descend the chute with a rolling motion 55 and will strike the lower wall of the slot 9. When this occurs the token will be rotated and as it turns the peripheral projection will pass through one or the other of the two notches 12 as soon as it registers 60 therewith so that the token can then pass into the lower portion of the chute, to facilitate which action said chute is deepened as at 13 below the trap, this deepening being obtained by expanding the forward or front 65 wall of said chute. By this deepening of the chute, by bulging for instance, the token can be projected across the lower wall or edge of the slot 9.

What I claim is:

1. A chute having an inclined portion, the upper wall of the chute in said inclined portion, having an elongated slot to receive a projection on a check rolling along said chute, the lower end of the slot being closed. 75
2. A coin-chute having a slot, constituting a trap, and having two transversely aligned notches extending outwardly therefrom.
3. A coin chute having a slot in its side constituting a trap, the lower end of the 80 slot being closed and the wall of the slot having a notch extending outwardly therefrom approximately at said lower closed end.
4. A coin-chute having a longitudinally extending slot, constituting a trap, the lower 85 end of the slot having a pair of outwardly extending notches and the chute being deepened below the lower wall of the slot.
5. A coin chute having an elongated slot constituting a trap, the lower end of the 90 slot having two outwardly extending notches and the chute below the lower wall of the slot being bulged outwardly.

In testimony whereof I affix my signature in presence of two witnesses.

GEORGE A. LONG.
